UNITED STATES PATENT OFFICE.

GEORGE SCHLEMMER, OF NEW YORK, N. Y.

REVERSIBLE UMBRELLA TIP GUARD.

Application filed June 12, 1924. Serial No. 719,550.

This invention relates to improvements in the means for retaining the tips of umbrellas or parasols, and the like, and it is the principal object of my invention to provide an elastic, reversible holder or guard for these tips which, when turned in one direction engages the tips of the umbrella ribs, and when reversed, or turned in the opposite direction, snugly engages the lower end of the umbrella handle.

It has been heretofore proposed to mount elastic rings or collars having cup-shape or bell-shape on umbrellas which in their operating position engage with a projecting ring in a groove of the umbrella handle.

These known devices show the disadvantages, that the umbrella handle must be specially prepared, that the engagement between collar and the tips was not at all times positive, so that when stamping the stick upon the pavement, the engagement was easily destroyed, and that the engagement between the collar and the handle was not at all times tight enough to be positive, and that the collar even after slight use only, was liable to be distorted and displaced and in this manner to lose its usefulness.

It is the object of my invention to do away with all of these disadvantages, and to provide a guard, which can easily be attached to any umbrella without the necessity of specially preparing the same, or by slipping it over any handle, a guard which will at all times securely grip over and guard the tips of the umbrella ribs, and which can readily be turned around or about its bottom part, constituting a quasi hinge, to either grip over the tips, or when reversed, to engage the lower end of the handle by tightly engaging the same.

Another object of the invention is the provision of a reversible holder or guard, the lower or inner face of which may have the color of the umbrella handle, while its outer or upper face may be colored to match the color of the umbrella, and in this manner present a pleasing appearance in both of its operating positions.

A further object of the invention is the provision of an annular body constituting a holder or tip guard provided with a peculiarly shaped bottom prepared from a suitable rubber blank so as to form a stationary member around which the movable walls of the body member may turn or be reversed in the manner of a hinge to either engage

the handle or the tips, as the case may be.

A still further object of the invention is the provision of an annular body member provided with an extension nipple adapted to securely engage the umbrella stick and to hold the device thereon.

These and other objects of my invention and advantages thereof will become more fully known as the description proceeds, and will then be specifically pointed out in the appended claim.

In the accompanying drawing forming a material part of this disclosure:

Figure 1 is a side elevation of a reversible tip guard constructed according to the present invention in position on an umbrella holding the tips together.

Figure 2 is a fragmentary sectional front elevation of the reversible tip guard in its tip guarding position, the section being taken on line 2-2 of Figure 1.

Figure 3 is a view similar to Figure 2 with the guard reversed to engage the handle.

Figure 4 is a top plan view of the guard constructed according to my invention.

Figure 5 is a detail view in section, illustrating on an enlarged scale the guard construction.

Figure 6 is a view similar to Figure 5 illustrating on an enlarged scale the construction of a modified form of guard.

An umbrella 10 of any ordinary, well known construction and type, equipped with the customary ribs 11 having upper end tips 12, has a stick 13 on which its handle 14 of any suitable material and shape or color is mounted in any preferred manner.

The reversible guard 15 is preferably made of elastic or semi-elastic material such as rubber, and is preferably annulus-shaped having an outer circular contour provided with a central opening 16 in its bottom part allowing the passage of the stick 13.

As best illustrated in Figure 5, the annular body 15 has a stationary bottom part 17 and a movable side wall or upstanding wall 18 united to the bottom or made integrally therewith. An annular groove 19 is formed within said bottom wall by means of a suitable die, so that a pivot or hinge point is presented around which the side wall may be turned in order to reverse the same in an obvious manner to either engage with its inner face the tips of the umbrella to hold the same firmly assembled about the stick,

or to engage the lower part of the handle when not in use as indicated in Figures 2 and 3, bottom and side wall blending by means of the bevel part 20.

5 In the form of my guard illustrated in Figure 6, the body of the guard is provided on its bottom part with an extending or projecting nipple 21 adapted to closely engage around the stick, and allowing a 10 folding of the side wall about the nipple and to unfold from the same, if it is desired to use the device non-reversible, either to engage the umbrella tips or to be disengaged therefrom without being slipped over the 15 handle end.

The operation of my novel guard will be entirely clear from the above description. If it is desired to attach the guard to an 20 umbrella, this is either done during the manufacture of the umbrella, or the annular body of the guard can be made of a material having sufficient elasticity to permit a widening of the opening 16 to such an extent that it may conveniently be slipped into 25 place over the umbrella handle. The guard may be colored so as to match the color of the umbrella when used as a tip guard, or to match the color of the handle when reversed, and engaging the handle, so for instance, the outside may be colored black, while the inner wall is tan-colored, etc. The 30 material of the guard will at all times guarantee a tight engagement between guard and

stick, and the shape and consistency of the material will at all times produce a snugly 35 engaging action between guard and tips or handle.

It will be clear that such changes may be made in the general arrangement and in the construction of the minor details of my 40 guard and in the material thereof, as fall within the scope of the appended claim without departing from the spirit of my invention.

What I claim as new and desire to protect 45 by Letters Patent is:

A tip guard for an umbrella consisting of a body of elastic material, said body having an interior portion provided with a central opening and the body being provided 50 upon its opposite surfaces with annular grooves which define the edges of said interior portion, the grooves upon the opposite surfaces of the body being of the same diameter and juxtaposed with relation to each 55 other whereby the body is thinned at the opposite sides of the median plane of the interior portion thereof, said body having a cylindrical wall portion which joins with the interior portion between the juxtaposed 60 grooves.

Signed at New York in the county of New York and State of New York this 5th day of June A. D. 1924.

GEORGE SCHLEMMER.
